UNITED STATES PATENT OFFICE.

AMOS H. HAWLEY, OF TERRE HAUTE, INDIANA, ASSIGNOR TO INTERNATIONAL MONEY MACHINE COMPANY, OF TERRE HAUTE, INDIANA.

RESERVE COIN-TRAY.

1,161,666.

Specification of Letters Patent.

Patented Nov. 23, 1915.

Application filed July 6, 1915. Serial No. 38,295.

To all whom it may concern:

Be it known that I, AMOS H. HAWLEY, a citizen of the United States, residing at Terre Haute, in the county of Vigo and State of Indiana, have invented certain new and useful Improvements in Reserve Coin-Trays, of which the following is a specification.

This invention has relation to machines for paying out money, especially those of the type embodying a suitable magazine to contain coins of different denominations adapted to be selected and delivered from the machine under the control of suitable predetermined mechanism.

In money paying machines of the above class such as are employed for making up payrolls, that is to pay out different amounts of money which in the aggregate often total many thousands of dollars for a complete payroll, it has been found that the coin magazine of ordinary capacity is not sufficient to hold enough money for the complete operation. This invention, therefore, has been designed with a view to providing a supplemental or reserve tray or magazine adapted to be detachably mounted upon the casing of the money paying machine and from which reserve tray or magazine the operator is enabled to replenish quickly the various holders or receptacles forming the main magazine of the machine.

With the above in view a preferred embodiment of the invention is illustrated in the accompanying drawings, in which—

Figure 1 is an end elevation showing a money paying machine, partly broken away as illustrated, having a reserve tray made in accordance with the invention applied thereto. Fig. 2 is a rear view of the same. Fig. 3 is a fragmentary front view showing more clearly the divisions or coin pockets into which the reserve tray structure is divided. Fig. 4 is a rear view partly broken away, showing the tray in folded condition. Fig. 5 is a sectional view taken about on the line 5—5 of Fig. 1, bringing out more clearly the adjusting means to hold the legs of the tray in collapsed and operative positions. Fig. 6 is a fragmentary sectional view illustrating in elevation the shorter legs of the tray folded thereagainst as when the device is not being used.

Usually a machine to which the present invention is particularly applicable is

equipped with a coin magazine holding about five thousand dollars in gold and other coins of ordinary denominations. For large payrolls, of course, the above amount is insufficient with which to pay out from the machine more than the amount representing the capacity of the main coin magazine, as above premised. The reserve coin tray of this invention is preferably located adjacent to the main coin magazine so that one of the operators of the machine, two of whom ordinarily handle the machine in a payroll operation, may with ease and facility quickly supply the various holders of the main magazine from the holders of the reserve tray preferably above the same. Since under certain conditions the reserve tray need not be used, as well as for purposes of portability, it is contemplated that the latter embody a collapsible structure to the extent at least that it is furnished with peculiarly mounted and adjustable supporting legs.

Describing the invention specifically, A in the drawings denotes the money paying machine, or that portion properly speaking to which the invention is applied, the casing only being illustrated in connection with a portion of the main coin magazine B. The magazine B is divided into pockets or receptacles containing pennies, nickels, dimes and practically all of the larger denominations of coins used in the United States system of coinage.

The reserve or supplemental tray of the invention as seen in Fig. 1 is preferably supported above the main magazine B, and is indicated at C. Said tray C is divided into coin receptacles or compartments 1 (see Fig. 3) and it is contemplated that any suitable arrangement of such pockets may be employed having in view the fact that of certain coins, especially pennies, a larger number is used than of other coins. At its lower corners the tray C is supplied with the forwardly and downwardly projecting arms 2 adapted to engage over end members 3 of the main coin magazine of the machine A, said arms 2 being intended to prevent any lengthwise displacement of the tray C once it is placed in position. Forward displacement of the tray is likewise prevented by lugs 4 projecting downward from the under sides of the arms 2 and engageable in rear of the magazine B as seen in Figs. 1 and 2. Mounted upon the rear side of the tray C are

the short supporting legs 5 and the long supporting legs 6. The front legs 5 are connected by a cross rod 5' and the rear legs by a similar cross rod 6', and each leg is preferably equipped with a rubber foot 7 to avoid liability of marring of the finish of the casing when the tray is positioned on or removed from the main machine A.

The legs 5 and 6 are foldable against the back of the tray C and since the connections between each pair of legs and the tray are substantially the same, one only will be described. Projecting rearwardly from the tray C are the brackets 8 each carrying a pivot pin 9 formed with a head 10. The pivot pin 9 is fixed on the bracket 8, and is formed with an enlargement 9' which is received by a slot 11 in the adjacent supporting leg. Said supporting leg furthermore is provided with a locking pin 12 connected by a coiled spring 13 with the first mentioned pin 9. The pin 12 has an enlargement 12' capable of engaging in either of two notches 8' formed on the edge of the bracket 8. When the pin 12 engages in the notch 8' nearer the tray C the adjacent supporting leg is supported in folded condition against the rear side of the tray, whereas when the said pin 12 engages the outermost of the said notches the leg is correspondingly held in operative position in which it supports the tray. The action of the connections intermediate the legs 5 and 6 and the brackets 8 is peculiar. Each pair of legs 5, or 6 as the case may be, is manipulated in folding or unfolding the same with respect to the tray C, the slots 11 permitting a longitudinal movement of the legs to disengage the locking pins 12 of the same from the notches 8' with which they may happen to be engaged, whereupon the pair of legs may be swung inwardly or outwardly as required to set up or knock down the tray C, the springs 13 forcibly causing the pins 12 to engage with the proper notches 8' after a pivotal movement of the pair of legs to the position in which it is required that the legs be adjusted. The shorter legs 5 preferably fold inside of the longer or rearmost legs 6 as seen in Fig. 4, and the simplicity of the arrangement and formation of the detail parts of the reserve tray is such as to facilitate the ready replacement or removal of the same in respect to the machine A.

Having thus described the invention, what is claimed is:

1. In a reserve coin tray for money machines the combination with the tray, of a supporting leg therefor, a bracket carried by the tray, a pivotal connection intermediate said bracket and leg, said leg being slotted to receive said pivotal connection, whereby longitudinal as well as pivotal movement of the leg is permitted, interlocking means intermediate the bracket and the

leg to hold the latter in adjusted positions, and spring means normally tending to impart said longitudinal movement to the leg whereby to maintain the interlocking means aforesaid operative.

70

2. In combination, a money paying machine, comprising a suitable casing and a coin magazine associated therewith, and a reserve coin tray comprising reserve coin holders, arms projecting forwardly and downwardly from the bottom of the tray to engage over the coin magazine, lugs projecting from said arms and engaging with the coin magazine at the rear thereof to prevent forward displacement of the tray, and supporting legs connected with the tray and resting upon the casing at the rear of the coin magazine.

75

3. In a reserve coin tray for money machines the combination with the tray, of a supporting leg therefor, a bracket carried by the tray, a pivotal connection intermediate said bracket and leg, said leg being slotted to receive said pivotal connection, whereby longitudinal as well as pivotal movement of the leg is permitted, interlocking means intermediate the bracket and the leg to hold the latter in adjusted positions and comprising a locking pin carried by the leg and interlockingly engageable with the bracket, 90 and a spring connected with said pin and normally tending to impart a longitudinal pull to the leg whereby to maintain said interlocking connection operative.

95

4. In combination a tray, a supporting leg 100 therefor, a bracket carried by the tray and formed with a notch in an edge portion thereof, a pivot member carried by said bracket and projecting from opposite sides thereof, the leg being formed with a slot receiving said pivot member at one side of the bracket whereby to establish a pivotal and slideable connection intermediate the leg and bracket parts, a locking pin projecting from said leg and having a portion adapted to engage in the notch of the bracket to hold the leg at a desired adjustment and to operate along the notched edge of the bracket during movement of the leg to and from such adjusted position, said locking member projecting beyond the bracket, and a coiled spring attached at one end to the portion of the pivot member opposite that engaging the leg and connected at its opposite end to the projecting portion of the locking member, 110 said spring normally tending to impart longitudinal movement to the leg whereby to maintain the locking member in engagement with the notch of the bracket.

115

5. A reserve coin tray for money paying 125 machines comprising a plurality of coin holders, projecting arms adapted to engage a coin magazine to properly position the tray in reference thereto, suitable legs carried by the tray, and connections interme- 130

diate said legs and the tray consisting of a bracket member projecting from the tray and formed with notches, pivot members on said bracket member, each leg having a slot through which said pivot member passes so as to permit longitudinal movement of the leg relative to the pivot member, a locking pin projecting from each leg and engageable with the said notches of the bracket member whereby to hold the leg folded against the tray or unfolded in operative position, and a spring connecting

the pivot member with said locking pin to maintain the leg in a predetermined position relative to said pivot member and to 15 cause coöperation of the locking pin with the notched portions of the bracket member.

In testimony whereof I affix my signature in presence of two witnesses.

AMOS H. HAWLEY.
